UNITED STATES PATENT OFFICE.

CHARLES W. BEHRENS, OF LANCASTER, OHIO, ASSIGNOR TO THE BEHRENS COMBINATION WAGON BED COMPANY, OF LANCASTER, OHIO, A CORPORATION OF OHIO.

WAGON-BODY.

SPECIFICATION forming part of Letters Patent No. 731,534, dated June 23, 1903.

Application filed December 29, 1902, Serial No. 136,993. (No model.)

To all whom it may concern:

Be it known that I, CHARLES W. BEHRENS, a citizen of the United States of America, and a resident of Lancaster, in the county of Fairfield and State of Ohio, have invented certain new and useful Improvements in Wagon-Bodies, of which the following is a specification.

The object of my invention is to provide means whereby a single wagon-body may be used with a flat bottom for the purposes for which a flat-bottom wagon are commonly employed or with a hopper-bottom for use as a dump-wagon in hauling soil, manure, &c.

15 The accepted construction of wagon running-gear necessitates that a hopper-bottom when used be raised to about the level of the bottom of the wagon-body, and the conditions under which a flat-bottom wagon is used require that the level of the bottom be kept as 20 low as possible and that the ability to convert it into a dump-wagon must not interfere to any extent with the use of the wagon with flat bottom either by decreasing its capacity 25 or increasing its weight.

For the purpose of accomplishing the change above indicated and to meet the conditions above named my invention comprises a wagon-body of proper construction having 30 a removable flat bottom and a removable hopper-bottom interchangeable with each other, the dump-bottom consisting of a dump-section and two end sections, which may be and by preference are also end sections of the flat 35 bottom, the dump-section being provided with means for suspending it from the wagon-body between the end sections, which are adapted to be inclined to discharge the contents of the wagon-body through the dump-section when 40 the bottom thereof is opened.

I also provide an improved means for closing and holding closed the gates of the dump-section; and my invention further consists in the construction, arrangement, and combination 45 of the several parts of which it is composed, as will be hereinafter more fully described and claimed, whereby I am enabled to remove from the wagon-body when used with a flat bottom all those parts not essential or 50 desirable for such use.

Referring to the accompanying drawings,

in which corresponding parts are designated by corresponding marks of reference, Figure 1 is a perspective view of a convertible wagon-body mounted on running-gear as it appears with its hopper-bottom. Fig. 2 is a perspective view of the removable dump-section. Fig. 3 is a plan view of the body shown in Fig. 1. Fig. 4 is a longitudinal central section on line $x^1 x^4$ of Fig. 3. Fig. 5 is a similar section 60 showing the body as it appears with a flat bottom. Fig. 6 is a perspective view of one of the removable cross-rests for the end sections of the hopper-bottom. Fig. 7 is a plan view similar to Fig. 3, but showing a form of my invention in which the dump-section is longitudinally carried in the wagon instead of transversely, as in Fig. 3. Fig. 8 is a longitudinal vertical section on line $x^8 x^8$ of Fig. 7. Fig. 9 is a transverse sectional section on 70 lines $x^9 x^9$ of Figs. 7 and 8. Fig. 10 is a perspective view of a cheek-plate used in connection with the removable longitudinal dump-section of Figs. 7, 8, and 9; and Figs. 11 and 12 are detailed views showing my preferred construction of the side stanchions 75 and eyes thereon.

The wagon-body consists of the main side-boards 1, the extension end-gate 2, the front gate 3, and the rear end-gate 4, the two latter 8c being similar in construction. The side-boards rest upon the cross-bars 5, the ends of which receive metal stanchions 6, extending up on the inside of the side-boards and having their ends projecting outwardly therefrom at the top and bottom in the form of eyes 6^a. The rear one of the end cross-bars 5 has an eyed bracket 7 on its center to receive the lower end of a cleat 8, secured to the extension end-gate 2, which may be locked 90 down by a split cotter-pin 9. Upper side-boards 10 are adapted to be carried above the main side-boards 1 by means of standards 11, fastened to the upper boards and having their lower ends adapted to be inserted in the 95 eyes 6^a of the stanchions 6, by which means the upper side boards will be removably secured in position. Their presence on the wagon-body is desirable both when used with a flat bottom and with a hopper-bottom, al- 100 though they may be removed, if desired.

The end-gates 3 and 4 are, as stated, simi-

lar in construction, and each is vertically movable in a slideway 12, formed on the side-boards 1 and 10. A lever 13 is pivoted on each end-gate 3 and 4 and has hinged there-
5 to on each side of its pivotal point a link 14, having its free end terminating in a hook 14^a, adapted to engage an eye 15 on the corre-
sponding side-board 10. One end of the lever 13 is prolonged to form a handle and bent
10 into a hook 13^a, adapted when the hooked ends of the links have been inserted in the eyes and the sides drawn together by a sweep
of the lever to be caught under one of the links and to be thus held. As the gate 4 is
15 located some distance in front of the exten-
sion end-gate 2, the boot 16 left between the
two may be used to advantage when shoveling
from the wagon when the latter is used
with a flat bottom in hauling grain, &c., the
20 gate 4 being partly raised to permit the pas-
sage of the grain to the boot.

The flat bottom of the wagon is removable
and rests upon the cross-bars 5, being by
preference composed of three sections, as
25 shown in Fig. 5—viz., two end sections 17
and a central section 18. The inner ends of
the end sections are chamfered and lie above
the corresponding chamfered ends of the mid-
20 dle section, so that the whole bottom may be
held down by pins 19, passing through cleats
20 on the bottom of the inner ends of the end
sections and into the middle cross-bars 5.

Connected and assembled as above de-
35 scribed with the flat bottom the wagon is
adapted for all the uses to which such a body
is generally employed, and at the same time
it may be readily converted to a dump-body
30 by removing the central bottom section 18
and replacing it by a dump-section 21 and re-
placing the flat end sections by slanting end
sections.

As stated, I prefer to use the same end sec-
tions 17 both with the flat bottom and with
the hopper-bottom, and this I accomplish by
45 providing cross-rests 22 near each end of the
wagon-body, having metal hooked ears 23 on
their ends, adapted to extend over the upper
edges of the side-boards 1, which may be
notched, as at 24, to properly position the
50 rests. The cleats 25 on the bottom of the
outer ends of the end sections 17 rest on these
rests, while the cleats 20 at the inner and lower
ends of the end sections rest on the two mid-
55 dle cross-bars 5, whereby the end sections are
supported. The bottom end sections 17 are
thus adjustable. I also provide the dump-
section 21, consisting of the cross-beam 26,
having hinged on each side thereof the dump-
60 gates 27, and removably hang it between the
slanting end sections 17 by means of end
hangers 28, provided at their upper ends with
hooked ears 29, resting upon the upper edges
of the lower side-boards, which may be notched
65 at 30 to properly position the dump-section.
As it is desirable to hang the dump-sections

as low as permitted by the running-gear of
the wagon, which brings the lower edges of
the gates below the lower edges of the side
bars, cheek-pieces 31 are provided, preferably
70 of sheet metal, which are fastened to the end
of the beam 26 and extending below the side-
boards form a downward extension thereof.
As shown in Fig. 2, the hinged joints between
the beam 26 and the gates 27 are protected by
75 the metal shields 32 and are formed by metal
straps 33, secured to the under surface of each
gate and each strap having its one end bent
in the form of a hook through an eye on the
end of a strap 34 on the under surface of the
80 cross-beam 26, the opposite ends of the straps
33 projecting beyond the lower edges of the
gates, and by abutting against the lower
edges of the end pieces 17 limiting the up-
ward movement of the gates.

An operating-shaft 35 projects upwardly
85 through the center of the cross-beam 26 and
is provided at its upper end with the crank-
handle 36, the lower end of the shaft being
below the beam, having rigidly attached
thereto the cross-head 37, which holds the
90 gates closed, a collar 38 being fastened upon
the shaft above the beam and bearing upon
the upper surface of the latter. The central
portion of the lower faces of the gates have
wearing-plates 39, provided with stop-lugs 40,
95 secured thereto, and when the shaft is so
turned as to cause the cross-head to lie across
the beam 26 the cross-head is located below
the gates and holds them up to close the bot-
tom of the wagon. By turning the shaft the
100 cross-head may be brought parallel with the
cross-beam and below it, so that the gates
will drop to discharge the load, and the cross-
head may again be turned at right angles to
the beam, when it will by running under the
105 gates throw them up.

It will be noted that the dump-section, with
its gates and operating means therefor, is
self-contained and may as a whole be readily
110 removed from and replaced in the wagon-
body and that the side-boards are held from
spreading both by the hooked ears on the
cross-rests and cross-beams and the described
construction of the fastener for the end-gate.

In Figs. 7, 8, 9, and 10 I have shown a modi-
fied form of my invention, in which the dump-
section is longitudinally supported in the
wagon-body. When used with a flat bottom,
the wagon-body is similar to the form before
described; but when it is desired to use the
hopper-bottom the two central cross-bars 5
are removed and supplemental cross-rests 22^a
are hung between the side-boards in the lower
ends of the hooked ears 23^a, the upper ends
of which are caught over the upper edge of
125 the side-boards 1, the rests 22^a serving as
rests for the lower ends of the end sections 17
of the bottom. The beam 26^a of the remov-
able dump-section is provided with hooks 28^a
upon its opposite ends, which rest upon the
130

central portions of the opposite supplemental rests 22^a, and carries upon each end a cheek-piece 31^a, preferably made of metal and having side flanges 41, inclined inwardly and 5 downwardly, and to the flanges at corresponding ends of the two oppositely-disposed cheek-pieces a longitudinal deflecting-board 42 is secured, a deflecting-board being thus located on each side of the gates 27^a, hinged to the 10 beam 26^a. As in this construction the gates have a considerable length, it is advisable to make them in two pairs and to use a separate shaft and cross-beam, such as before described, for each pair, and I have therefore 15 shown two shafts 35 in Figs. 7 and 8.

In Figs. 11 and 12 I have shown my preferred method of constructing the eyes 6^b upon the stanchion 6. As shown therein, the cross-bar 5 has secured to its end a metal cap 20 forming the eyes 6^b, over which the apertured lower end of stanchion 6 is slipped, the stanchion having a flange 6^c struck up therefrom around its aperture, through which flange and cap and cross-bar a bolt 6^a is passed to 25 hold the plates together.

Having thus described my invention, what I claim, and desire to secure by Letters Patent, is—

1. In a convertible flat and dump bottom 30 wagon, the combination with a wagon-body, of a removable dump-section having pivoted gates, which when the dump-section is in place in the wagon-body form a part of the bottom thereof, substantially as described.

35 2. A wagon-body having its bottom consisting of a removable dump-section and adjustable end sections, substantially as described.

3. In a wagon-body, the combination with 40 side-boards, of a removable dump-section having a pivoted gate in the bottom of the body and actuating means for the dump-gate carried by the dump-section, substantially as described.

4. In a wagon-body, the combination with 45 side-boards, of a bottom consisting of adjustable end sections, and a removable dump-section with a pivoted gate, and operating means for the gate of the dump-section carried by the dump-section, substantially as described.

50 5. In a convertible flat and dump bottom wagon, the combination with the wagon-body, of a dump-section having pivoted bottom gates removably hung in the body, substantially as described.

55 6. In a convertible flat-bottom wagon, the combination with the wagon-body having side-boards, of a dump-section having pivoted bottom gates removably hung in the wagon-body from the side-boards, substantially as described.

60 7. In a wagon-body, the combination with side-boards, of a bottom consisting of adjustable end sections, removable cross-rests for supporting the end sections, and a removable dump-section, consisting of a beam having a

gate hinged thereto and provided with supporting-hangers upon its ends adapted to engage the wagon-body, and operating mechanism for the gate carried by the beam and removable from the wagon-body therewith, 70 substantially as described.

8. A dump-section of a wagon-body, consisting of a central beam having supporting-hangers upon its ends, and having a gate hinged thereto, and operating means for the 75 gate carried by the beam, substantially as described.

9. A dump-section of a wagon-body, consisting of a central beam having supporting-hangers upon its ends, and having gates hinged 80 thereto, and operating means for the gates comprising a vertical shaft carried by the beam and a cross-head upon the shaft below the gates, substantially as described.

10. In a dump-wagon, the combination with 85 a central beam, and gates hinged thereto on opposite sides, of a vertical shaft, and a cross-head carried by the shaft below the gates and adapted to operate thereon, substantially as described.

11. In a dump-wagon, the combination with 90 a central beam, and gates hinged thereto on opposite sides, of a vertical shaft extending through and carried by the beam and a cross-head on the shaft beneath the beam to lift and 95 retain the gates, substantially as described.

12. In a dump-wagon, the combination with a beam, having eyed straps thereon, of a gate having straps provided at one end with hooks engaging the eyes on the strap on the beam, 100 the opposite ends of the straps projecting to form limit-stops for the gate, substantially as described.

13. In a dump-wagon, the combination with 105 a beam, provided with means for detachably securing it in place, of cheek-plates at the end of the beam, a gate hinged to the beam, and operating means for the gate carried upon the beam, substantially as described.

14. In a dump-wagon, the combination with 110 a wagon-body consisting of side-boards and cross-bars, of cross-rests provided with means for removably hanging them in the wagon-body from the side-boards, bottom end sections adapted to be supported on the cross-bars and cross-rests, and a removable hopper-section, consisting of a beam provided with means for removably hanging it from the side-boards, and having end cheek-plates and gates, and operating means for the gates 115 carried upon the beam, substantially as described.

15. In a dump-wagon, the combination with 120 side-boards having eyes therein, and cross-beams, of end-gates, a lever pivoted to each 125 end-gate, links hinged to each of the levers on opposite sides of their pivotal points, and having hooks to engage the eyes on the side-boards, a hook upon each of the levers adapted to engage one of the corresponding links, 130

whereby the side-boards may be drawn together, cross-rests provided with means for removably hanging them from the side-boards, bottom end sections adapted to be supported on the cross-beams and cross-rests, and a removable hopper-section, consisting of a beam provided with means for removably hanging it from the side-boards, and having end cheek-

plates and gates and operating means for the gates, substantially as described.

Signed by me at Lancaster, Ohio, this 21st day of October, 1902.

CHAS. W. BEHRENS.
